UNITED STATES PATENT OFFICE.

SWEN WILLIAM ANDERSON, OF SALT LAKE CITY, UTAH.

WASHING-MACHINE.

SPECIFICATION forming part of Letters Patent No. 769,883, dated September 13, 1904.

Application filed July 8, 1903. Serial No. 164,669. (No model.)

To all whom it may concern:

Be it known that I, SWEN WILLIAM ANDERSON, a citizen of the United States, residing at Salt Lake City, in the county of Salt Lake and State of Utah, have invented certain new and useful Improvements in Washing-Machines, of which the following is a specification, such as will enable those skilled in the art to which it appertains to make and use the same.

This invention relates to washing-machines; and the object thereof is to provide an improved machine of this class which is simple in construction and operation and also strong and durable and will not get out of order or frequently need repairs.

The invention is fully disclosed in the following specification, of which the accompanying drawings form a part, in which the separate parts are designated by suitable reference characters, and in which—

Figure 1 is a top view of my machine and shows same partly in section and parts broken away to better illustrate its mechanism. Fig. 2 is a cross-section taken on line 2 2 of Fig. 1; Fig. 3, a view of a part of the movable cover, and Fig. 4 is a view of that part of the machine in which a part of the cover engages.

My machine consists, essentially, of a box or receptacle *a*, supported upon the legs *a*² and having upwardly-extending side pieces *b*, which carry a shaft or spindle *b*². The said spindle is provided with a crank-handle *b*³ at one end and locking-cleat *b*⁴, whose function will be hereinafter explained. Secured to the box or receptacle directly above same are supplemental sides *c*, having extending end portions *c*², which carry a shaft *c*³, upon which is secured the wheels *d* and *e*, and one outer end of the shaft *c*³ is provided with a driving-wheel *c*⁴, having a handle *c*⁵. The wheels *d* and *e* are arranged alternately upon the shaft *c*³ and are provided with pins *d*² and *e*², respectively, and these pins *d*² and *e*² are adapted to engage the ends of the levers *d*³ and *e*³, respectively, which are mounted, by means of pins *f*², in supports *f*, secured to cross-pieces *f*³, which are in turn secured to the supplemental sides *c*. The inner ends of the levers *d*³ and *e*³ engage with lugs *g*² and *h*², respectively, which are formed upon the frame mem-

bers *g* and *h*. The frame members are movably mounted between cross-pieces *f*³ and *i*, which are slotted at *i*² to receive them. To the lower ends of the frame members *g* and *h* are fastened what I shall designate as "pounders" *p*² and *h*², respectively.

Securely fastened to the frame members *g* and *h* are upwardly-extending rods *j*, which pass vertically through a cross-piece *j*² and which are provided with springs *j*³, which are designed to keep the pounders *p*² normally in their lowered position and to facilitate their descent when released. Attached to the frame members *h* at *k* are the cords *k*², which are also connected to the spindle *b*² and are adapted to raise the frame members *g* and *h* when said spindle is turned. The cleat *b*⁴ is provided to lock the handle *b*³ when it is desired to keep the frame members in a raised position.

A movable cover or partition *m*, having a handle *m*³ and an overlapping end portion *m*⁵, which is adapted to engage in the recess *m*⁴, formed in the sides of the body or receptacle *a*, is held in place in the said receptacle by means of the cleat *m*² and said overlapping end portion *m*⁵ and recess *m*⁴, and this partition divides the receptacle into a front and back compartment. The overlapping end portion *m*⁵ of the partition *m* is clearly shown in part in Fig. 3, and the recess *m*⁴ is clearly shown in the partial side view and section in Fig. 4, while the partition *m* is shown in position in Fig. 2. The recess *m*⁴ and the cleat *m*², which are adapted to hold the partition *m* in position, are clearly shown in Fig. 1.

In the operation of my machine before the clothes are placed in the same the pounders *g*² and *h*² are raised to their highest position by means of the spindle *b*² and the cords *k*² and are locked in this raised position by means of the cleat *b*⁴ engaging the handle *b*³. The clothes are then placed in the receptacle *a*, and if the cover *m* is used the clothes are all forced back behind the cover and under the said pounders. The cover, however, need not be used if not desired. The handle *b*³ is then released, allowing the pounders to descend to their lowest position against the clothes in the receptacle *a*. The operation of

the machine is then started by turning the driving-wheel c^4 in the direction indicated by the arrow x . The operation will rotate the wheels d and e and cause the pins d^2 and e^2 to alternately engage the levers d^3 and e^3 , which raise the pounders p^2 and h^2 , respectively. As said pins pass or disengage the levers the pounders are released and drop very quickly and with considerable force by action of gravity and pressure of the springs j^3 upon the clothes in the receptacle a . The alternate pounding action of the pounders p^2 and h^2 upon the clothes produces an agitation which causes the cleansing liquid to circulate through the clothes and effectively clean them. During the process of cleaning the liquid used may be changed as often as desired and may be drawn off by removing the plug p .

The machine may be made of any desired material, and various other changes in and modifications of the construction herein described may be made without departing from the spirit of my invention or sacrificing its advantages, and I reserve the right to make all such alterations therein as fairly come within the scope of my invention.

Having fully described my invention, what I claim as new, and desire to secure by Letters Patent, is—

30 1. A washing-machine of the class described, comprising a receptacle, vertically-movable frame members mounted in the back portion of the receptacle and provided with laterally-extending projections, vertically -arranged shafts connected with said vertically-movable members and provided at the lower ends with

pounders, springs for depressing said vertically-movable frame members and shafts, levers mounted in the back wall of the back compartment and adapted to operate in connection with said laterally-extending projections, and means for operating said levers alternately, substantially as shown and described.

2. A washing-machine of the class described, 45 comprising a receptacle, vertically-movable frame members mounted in said receptacle and provided with laterally-directed projections, vertically -arranged shafts connected with said vertical members and provided at 50 the lower ends with pounders, springs for depressing said shafts, levers mounted in the back wall of said receptacle and adapted to operate in connection with said projections, and means for operating said levers alternately, comprising a horizontally -arranged shaft mounted rearwardly of said receptacle and provided with wheels or disks which are secured thereto, said wheels or disks being provided with laterally-projecting pins which 55 operate in connection with the outer ends of said levers, substantially as shown and described.

In testimony that I claim the foregoing as my invention I have signed my name, in presence of the subscribing witnesses, this 1st day of July, 1903.

SWEN WILLIAM ANDERSON.
